UNITED STATES PATENT OFFICE.

HARRY WARD, OF NEWARK, NEW JERSEY, ASSIGNOR TO OSCAR E. A. WIESSNER, OF BROOKLYN, NEW YORK.

DESIGN FOR A HEADBOARD OR FOOTBOARD FOR BEDSTEADS.

SPECIFICATION forming part of Design No. 28,107, dated December 28, 1897.

Application filed November 16, 1897. Serial No. 658,761. Term of patent 3½ years.

To all whom it may concern:

Be it known that I, HARRY WARD, a citizen of the United States, and a resident of Newark, in the county of Essex and State of New Jersey, have invented a certain new and useful Design for a Headboard or Footboard for Bedsteads, of which the following is a specification.

This invention relates to a design for a headboard or footboard of a metallic bedstead and is illustrated in the accompanying drawing, which forms a part of this specification.

In the drawing, A indicates the posts, which are tipped with mounts B, having oblong beads vertically arranged about their middle and terminated below with conventional leaves C, said mass being surmounted by an urn-shaped finial D, having a beaded top and a leaf design about the bowl thereof.

At the lower ends of the posts are beaded bands E, surmounted by conventional leaves. On each post, at a short distance above said bands E, is located a band F, of larger diameter, in which the beads are somewhat longer. This band is terminated at each end by conventional leaves. On each post, also at a short distance below the mount B, is a beaded band terminated at each end by conventional leaves, the whole being of the same design as that last described, but of a smaller size.

A rail, as G, extends from one post A to the other, with which posts it is joined between the bands E and F. At the middle of this rail G there arises an arched rod H, which extends to nearly the height of the post A. Under the arch formed by this rod is a scroll design K, having in each of its lower corners a cherub. Extending from one side of the arch to the other just below this design is a short rail I, from the middle of which there extends to the exact middle of the rail G a vertical rod J. In the panels formed by the rods H and J and the rails G and I are scroll-shaped figures L, supported by the rods H and J, respectively.

Extending from each post A at the mount B there are horizontal rails M, which meet

the base of the arch in the rod H, and concentric with said arch and above the same is an arched rod N, which rests at its ends upon the rails M. Between the arched portion of rod H and the arch N are radially-mounted urn-shaped spindles O, each bearing a leaf design. Parallel to each post A there is a vertical rod P, which extends from the rail M to the rail G. At a short distance below the rail M there is a cross-rail Q, which extends from the rod P to the rod H, and at a short distance below the rail Q is another rail R, which also extends from the rail P to the rail H, and between the rails Q and R are vertically-arranged urn-shaped spindles S, having beaded tops and bases and a leaf-pattern band near their middle.

Below the rails R are rails T, parallel thereto, and between which and the rails R are scroll-patterns K', each having at the lower corners cherubim. Extending from the middle of each rail T to the rail G is a rod U. At the junctions of the rods U and the rails T and the rods P and the rails N are beaded fan-shaped chils V, each surmounted by a beaded finial and bearing upon its face a cherub's head.

At the junctions of the rail R with the rod H are mounted chils B', like unto the chils V save that the finial is omitted.

At the junctions of the rods J, H, U, and P with the rails G, K, I, T, R, and Q there are located beaded chils W, and on the rails opposite to said chils are globe-shaped projections or buttons X. Similar buttons are also found opposite the ends of the arched rod N and opposite the upper ends of the spindles O and S.

I claim as my invention—

A design for a headboard or footboard of a bedstead, substantially as herein shown and described.

Signed at New York, in the county of New York and State of New York, this 8th day of November, A. D. 1897.

HARRY WARD.
